LACE ATTACHMENT FOR FULL FASHIONED
KNITTING MACHINES

Gottlob Bitzer, Wyomissing, Pa., assignor to Textile Machine Works, Wyomissing, Pa., a corporation of Pennsylvania

Application May 4, 1933, Serial No. 669,290

11 Claims. (Cl. 66—96)

This invention relates to full fashioned hosiery knitting machines, and more particularly to a lace attachment adapted to function in conjunction with and under control of certain elements of the knitting machine, for producing a wide and varied range of designs in the hosiery knit-
5 thereby.

The lace attachment to which the present invention is particularly adaptable is shown and 10 described in the assignee's copending application, Serial No. 561,536, filed September 8, 1931. The lace attachment disclosed in the said copending application primarily comprises a longitudinally 15 slidable bar provided with a series of points adapted to lift knitted stitches from predetermined needles of the machine and to deposit such stitches on others of the needles, under control of a design cam which actuates the slide bar to align the transfer points with the desired needles in 20 each instance.

The number of relatively different movements capable of being imparted to a cam follower by a single cam in a single cycle of operation thereof is determined by the character and the extent of 25 the required movements and by the amount of available camming surface afforded by the cam element, the amount of camming surface in turn being determined by the diameter of the cam element, especially where the cam element is of the 30 disc type and the cam follower engages the peripheral edge of the disc. The diameter of the cam disc is frequently controlled by the amount of available clearance in the device of which the cam is a part, while in other instances the diameter of the cam is purposely restricted in order 35 to make the device, as a whole, in the most compact form consistent with practicability and efficiency.

In the device with which the present invention 40 is particularly concerned, compactness is desirable, and in order to provide a wide range of design, necessitating a large number of different positionings of the transfer points relative to the needles of the machine, a plurality of axially aligned disc cams of relatively small diameter each is employed. A single cam follower operatively associated with the longitudinal slidable point bar cooperates with the plurality of cams and is arranged to be shifted laterally from the 45 plane of one of the disc cams to the plane of another of the cams, each cam disc providing for as great a number of different movements of the point bar as is possible within the amount of available camming surface afforded by the peripheral edge of the disc, whereby successive, alternate, or 50 selective engagement of the single cam follower with the different cam discs will, as a whole, provide the necessary large number of different movements for the point bar.

55 In the device disclosed in the above noted co-

pending application the cam follower is arranged to be moved manually from alignment with one of the cam discs to alignment with another of the cam discs. Such manual shifting of the cam follower necessitates the operator's watching the progressive development of the design carefully to avoid repeating that portion of the design developed in the fabric by any single one of the cams. 5

In order to shift the cam follower in the manner noted the machine must be stopped during the shifting operation, which results in a loss of 10 time and production.

The object of the present invention is to provide means for automatically shifting the cam follower without interrupting the normal operation of the machine. 15

Another object of the invention is to provide means, in the form of a master cam, for automatically making the selection of the design cam 20 to be engaged by the cam follower, whereby more intricate designs may be produced which will require the use of all the cams in succession or one or more of the cam discs two or more times successively, or various cams in an irregular pre-arranged order, within a single repeat of the 25 design as a whole.

The operation of the lace attachment in general, and the improvements to be covered by the present application in particular, will be fully 30 disclosed hereinafter, reference being had to the accompanying drawings, of which:

Fig. 1 is a transverse sectional elevation of sufficient of a full fashioned hosiery knitting machine of conventional type to illustrate the lace attachment and improvements according to 35 the present invention as applied thereto;

Fig. 2 is a fragmentary plan view drawn to an enlarged scale and illustrating the lace attachment and improvements more in detail; 40

Fig. 3 is a front elevation of the mechanism shown in Fig. 2;

Fig. 4 is a rear elevation of a portion of the mechanism shown in Figs. 2 and 3;

Fig. 5 is an end elevation of a portion of a mechanism shown in Fig. 4 as viewed from the left; and 45

Fig. 6 is a sectional elevation taken on the line 6—6, Fig. 4.

Conventional types of flat full fashioned hosiery knitting machines each include a main cam shaft 1, which is provided with a series of cams arranged, under normal knitting conditions, to actuate the bank of needles 2 and other cooperating elements (not shown) to produce course after course of stitches of which the stocking fabric is composed. 50

In order to narrow the fabric, in providing for the fashioning of the stocking, stitches are lifted from the needles on which they were formed at 55

and adjacent each of the opposite selvage edges of the fabric, such stitches being transferred onto other needles inwardly disposed with respect to those from which the stitches had been lifted.

5 The narrowing mechanism and the mechanism for dipping the transfer points, by which the selvage stitches are transferred from needle to needle, are operated by and under control of a second series of cams rigidly secured to the main cam shaft 1.

10 In order to effect narrowing of the fabric by the second series of cams on the shaft 1, the said shaft is shogged longitudinally to align the cam followers cooperating with the first series of cams with complete circular discs on the cam shaft, whereby the stitch-forming mechanism becomes inoperative, as the longitudinal shogging of the cam shaft 1 brings the second series of cams thereon into alignment with cam followers through which the dipping actions of the transfer points and the inward narrowing movements of the transfer points are effected.

15 Operation of the lace attachment disclosed in the above noted copending application, and in the present application, is effected by the second above noted series of cams on the main cam shaft 1 when such shaft is shogged in the manner above noted. However, at such time, the regular narrowing points are moved to an inoperative position and the narrowing mechanisms, by which the narrowing points are moved inwardly, are thrown out of operation and a set of lace points, illustrated at 3 in the present case, are moved into position to engage and lift stitches from certain of the needles 2 and to transfer such stitches to other adjacently disposed needles in the bank thereof.

20 In the present instance, the lace points 3 are carried by point holders 4 which are rigidly secured to a shaft 5, which is mounted in bearings 6 rigidly secured to the front rod 7 of the usual dipping mechanism found in machines of the type noted. The rod 7 also carries supports 8 in which the bars 9, 9 for the regular narrowing points are slidably mounted.

25 The point rod 5, in addition to a possible rotary motion for throwing the lace points 3 out of operation, is arranged for longitudinal sliding movement in the brackets 6 for shifting the lace points 3 as a unit from alignment with certain of the needles 2 into alignment with others of the needles, between the dipping motion of the rod 7, by which the points 3 lift the stitches from the selected needles 2 and a second dipping motion 30 of the rod 7 whereby the points 3 place the lifted stitches on adjacent needles, in the course of formation of the lace design in the fabric.

35 Longitudinal movement of the point bar 5 is effected by the mechanism shown in Figs. 2, 3 and 4 particularly. The dipping bar 7, as usual in this type of machine, is fixed, insofar as rotation about its own axis and longitudinal movement is concerned. The rod 7, however, is permitted bodily lateral movement through an arc struck from the center of the dipping shaft 10, which is provided for in the usual manner, whereby the above noted dipping action of the points 3 relative to the needles 2 is effected.

40 Rigidly secured to the dipping rod 7 is a bracket 11 which is provided with a bearing 12 for rigidly supporting a transversely extending shaft 13.

45 In order to facilitate assembly of the parts of the mechanism hereinafter described, the shaft 13 is formed in two sections 13b and 13c (see Fig. 6). These sections are threaded into opposite

5 sides of the bracket 11, and secured therein, as indicated at 13d and 13e, respectively. For convenience herein, however, said shaft will be referred to as a unit, by the numeral 13, since it is evident that the parts 13b and 13c could be formed in one piece if desired.

50 Rotatably mounted on the shaft 13 is a ratchet wheel 17 which is provided with a hub 17a having secured thereto a series of design cams, in the present instance three in number, illustrated at 14, 15 and 16 respectively. The design cams are rigidly joined to the hub 17a by means of a plurality of suitable bolts 17b which extend transversely through the cams and a large diameter portion 17c of the hub 17a and thence into the 15 abutting side of the ratchet wheel 17. These bolts are readily removable for disassembly of the cams and ratchet when desired. One end of the hub 17a is held in frictional engagement with one end of the bearing 12 by means of the resilient plate or brake element 18 engaging the opposite end of the hub 17a of the ratchet wheel 17, the pressure of said brake being determined by a nut 19 threaded on the shaft 13, whereby the said ratchet wheel and cam discs are 20 maintained in a fixed position during reverse movements of a pawl 20, by which intermittent rotation of the ratchet wheel 17 and design cams 14, 15 and 16 in one direction is effected.

55 The pawl 20 is pivotally mounted at 21 on a 30 rocker 22 which in turn is pivotally mounted on the hub 17a of the ratchet wheel 17. The rocker 22 is rocked in one direction by a spring 23 having one end attached to the rocker 22 and its opposite end secured to an anchorage 24 which is secured 35 to the dipping rod 7.

60 Rocking of the arm 22 in an opposite direction, to advance the design cams 14, 15 and 16 step by step in accordance with the spacing of the teeth of the ratchet wheel 17, is effected by a bell-crank 40 lever 25 which is pivotally mounted on the bracket 11 with one arm 26 of said bell-crank lever underlying and engaging an arm 27 formed on and extending from the rocker 22, the second arm 28 of the bell-crank lever 25 lying in engagement with a pin 29 mounted in and extending laterally from a lever 30 which is loosely mounted on the dipping rod 7.

65 Pivots attached to the arm 30, by the pin 29, is one end of an actuating link 31. The opposite 50 end of the link 31 is pivotally connected to a lever 32 which is pivotally mounted on the back dipping shaft 10. Pivots attached to the lever 32 is one end of a link 33, the opposite end of which is pivotally connected to one arm 34 of a lever 35. The lever 35 is pivotally mounted at 36 to a fixed portion of the machine. The second arm 37 of the lever 35 is provided with a cam follower 38 which is adapted to be engaged by a cam 39 secured to the main cam shaft 1, whereby each revolution of said cam shaft, while said shaft is in its shogged position, through the system of levers, links, rocker and pawl just described causes simultaneous rotation of the design cams 14, 15 and 16 to the extent of one tooth 65 of the ratchet wheel 17.

70 At one side of the design cams 14, 15 and 16, and adapted to be engaged by any one thereof, is a cam follower 40. The cam follower 40 is rotatably mounted on a shaft 41 which is rigidly secured in the arms 42, 42 of a yoke head 43 formed at one end of a point rod actuating lever 44.

75 The point rod actuating lever 44 is pivoted at 45 75

to the bracket 11 and is provided with a depending arm 46 which is adapted to engage a collar 47 adjustably mounted on the point shaft 5, operative contact between the arm 46 and the collar 47 being maintained by a spring 48 which is attached to a frame member (not shown) and a lever 49 whose one end 49a bears against a collar 49b fixed on shaft 5.

The cam follower 40, in the present instance a roller, is freely rotatably mounted on the shaft 41 and is adapted to be shifted laterally, between the limits determined by the fork ends 42, 42 of the lever 44, and for this purpose a shift rod 50 is slidably mounted in the arms 42, 42 in substantially parallel relation to the shaft 41.

The shift rod 50 is grooved, at 51, to receive the edge of the roller 40 while permitting free rotation of the roller within the groove. Longitudinal movement of the shift rod 50 slides the roller 40 along its shaft 41, from alignment with and in the plane of one of the cam discs 14, 15 or 16, as the case may be, into the plane of and in alignment with one other of said cam discs, under selective control of mechanism hereinafter described.

Secured to the one end of the shift rod 50 is a clamp block 52 from which vertically projects a pin 53, which, under certain circumstances as hereinafter noted, may be employed as a handle for manually sliding the shift rod 50 and consequently the roller 40 axially of the shaft 41.

Pivotedly mounted at 54 on the bracket 11 is a double arm lever 55, one arm of which is forked as indicated at 56 (see Fig. 2) to receive the actuating pin 53. The second arm of the lever 55 has pivotally mounted thereon a roller 57 which is engaged by a master cam 58. A suitable spring 57a is provided between the mounting for the roller 57 and the end of the shaft 13, to maintain the roller in engagement with the master cam 58. The master cam 58 is rotatably mounted on the shaft 13. Integrally attached to the master cam 58 for rotation therewith, is a ratchet wheel 59.

The ratchet wheel 59 is adapted to be engaged by a pawl 60 which is pivotally mounted on the rocker 22, a clamp brake 61 being provided to maintain the ratchet wheel 59 and master cam 58 in a substantially fixed position on the shaft 13 between intermittent movements of the said ratchet wheel and master cam as effected by the pawl 60, under predetermined circumstances, when the rocker 22 is rocked in the manner above noted. The pawl 60 is loosely mounted on a stud 62 projecting laterally from the rocker 22.

Loosely mounted on the stud 62 intermediate the pawl 60 and rocker 22 is a pawl-controlling or hold-out arm 64. The hub of the hold-out arm 64 is shouldered, as illustrated at 65 in Fig. 2, which shoulder cooperates with a shoulder 66 formed on the hub of the pawl 60. The rocker 22 is provided with a hook-like extension 67 to which is connected one end of a spring 68, the opposite end of said spring being connected to the hold-out arm 64 and tending at all times to rotate said arm about the axis of the stud 62 and into contact with a stop screw 69, through the coaction of the shoulders 65 and 66 on the hub of the hold-out lever 64 and the hub of the pawl 60 respectively. The pawl 60 is held out of engagement with the ratchet wheel 59 during each complete revolution of the cam unit, composed of the integrally connected cams 14, 15 and 16, as effected in intermittent steps by engagement of the pawl 20 with the ratchet wheel 59.

The front cam 14 of the cam unit including

the cams 14, 15 and 16 is provided with a laterally extending cam surface 70 which, as the cam unit approaches the end of each complete revolution, engages an inclined cam surface 71 on a laterally extending projection 72 formed on the lower end of the hold-out arm 64.

When the cam unit completes a full revolution and attains the position shown in Fig. 3 the cam surface 70 has moved across the inclined surface 71 and to a position outside the projection 72 on the hold-out arm 64, thereby rocking the hold-out arm 64 about the stud 62 and away from the stop screw 69. In so doing the shoulder 65 of the hold-out arm 64 moves away from the shoulder 66 on the pawl 60, thereby permitting the pawl 60 to drop, by gravity, into contact with the ratchet wheel 59, as shown in Fig. 4.

The cam surface 70 is formed on a cam piece 75 carried by the outer cam 14 of the cam unit and while the heel 76 of the cam piece 75 is holding the pawl control lever 64 in a position to free the pawl 60, the point 77 of the said cam piece 75 engages a collar roller 78 mounted on the shaft 41, on which the cam follower 40 is also mounted.

Upon the next rocking movement of the rocker 22 the pawls 20 and 60, then in engagement with the ratchet wheels 17 and 59 respectively, effect a one step movement of each of the ratchet wheels and consequently a one step rotation of the cam unit including cams 14, 15, 16 and a simultaneous movement of the master cam 58.

The above noted movement of the cam unit 14-15-16 causes the cam piece 75 to rock the lever 44 slightly about its pivot and sufficiently to release the cam follower 40 from the periphery of the cam disc 14, 15 or 16, as the case may be. At the same time the one step movement of the master cam 58 effects a rocking motion of the lever 55 about its pivot 54, causing a longitudinal shifting movement of the shift rod 50, whereby the cam follower 40 is shifted laterally from one of the cams of the unit to another of said cams, in accordance with the length of the radius described by the portion of the camming surface of the cam 58 then engaging the cam follower 57 of the shift lever 55.

As soon as the shift of the cam follower 40 is completed the cam piece 75 moves away from the collar 78, permitting the lever 44 to rock in the opposite direction, thereby bringing the cam 40 into operative engagement with the newly selected cam of the unit as determined by the camming surface of the master cam 58.

At the same time as the point 77 of the cam piece 75 moves away from the collar 78 the heel 76 of the said cam piece 75 rides off the lower end of the projection 72 of the pawl control lever 64, whereupon the spring 68 returns the pawl control lever 64 into its quiescent pawl-retracting position in engagement with the stop screw 69. In so doing the shoulder 65 again engages the shoulder 66 of the pawl 60 and thereby lifts the pawl 60 out of engagement with the ratchet wheel 59, in which ineffective position the said pawl is maintained until the next complete revolution of the cam unit 14-15-16 is completed, whereupon the operations above noted will be repeated to shift the cam follower 40 into operative alignment or engagement with another of the cams 14, 15 or 16 of the unit as selectively determined by the camming surface of the master cam 58.

From the above, it will be apparent that by

providing a maximum number of varying elevations and depressions, radially speaking, on each of the cams 14, 15 and 16 and a maximum number of varying elevations and depressions on the master cam 58, whereby the cam follower 40 may be selectively brought into correlation with any one of the cams 14, 15 and 16 at the end of each complete revolution of the cam unit, a practically unlimited number of different positionings of the lace points 3 relative to the needles 2 may be provided. Furthermore the selection of the cam is effected without interrupting the normal operation of the machine.

In some instances, one of the cams of the unit may be reserved for producing one particular class of stitch formation once, twice, or repeatedly throughout the knitting of a stocking, without the use of the other cams of the unit. For example, the cam 16 may be reserved for the formation of a "picot" edge, in which case the cam follower 40 may be moved into alignment with the cam 16 at the proper time, in the knitting of the stocking, by the master cam 58, but in instances where this picot edge formation of stitch is to be repeated constantly throughout the formation of the stocking, to give a certain design effect in the fabric, the cam follower 40 may be brought into alignment with the cam 16 manually, in which case the pin 53 on the shift rod 50 is used as a finger grip or handle for sliding the shift rod 50, and consequently the cam follower 40, longitudinally of the shaft 41 to bring the roller 40 into alignment with the cam 16.

In addition to its longitudinal movement the shift rod 50 is permitted a certain amount of rotary motion, in the fork arms 42, 42 of the lever 44. Such motion is limited by a depending pin 80 which is held in contact with one side of the shaft or pin 41 by a spring 81 (see Figs. 4 and 5). When the roller 40 is aligned with the cam 16 under such circumstances the depending pin or arm 80 acts as a latch and snaps into a circumferential groove 82 formed in the shaft 41 adjacent the outer projecting end thereof, by action of the spring 81, whereby the cam roller 40 is held indefinitely in alignment with the cam 16 and the master cam 58 then becomes ineffective, by reason of the fact that the shift arm 55, as a result of the manual operation of the cam follower 40, is swung about its pivot 54 and the cam follower 57 is thereby carried away from the camming surface of the master cam 58.

When the cam 16 is to be reserved for the special purpose other designs to be produced in the stocking are confined to the cams 14 and 15, or to any other number of cams when a greater number is provided in the unit, but in cases where all the cams of the unit are to be used selectively for producing a continuous design the latch pin 80 may be kept from entering the keeper groove 82 by any suitable means, or in any suitable manner. As an example, the set screw 83 which holds the rod or shaft 41 rigidly in the arms 42, 42 of the lever 44 may be released to permit the shaft 41 to be moved outwardly beyond the maximum outward position attained by the pin 80, after which the shaft 41 may again be locked by resetting of the screw 83. In this manner all the cams in the unit may be selectively employed in the formation of a predetermined design in the stocking fabric.

The mechanism for shifting the main cam shaft 1 of the machine, as shown in Fig. 1, is substantially the same as the shaft shogging motion of the conventional knitting machine of the type

noted and for this reason detailed explanation of the operation thereof is deemed unnecessary, except to state that the usual pattern chain 85 is employed which carries the buttons usually employed to effect the operation of the shogging motion to shog the shaft when ordinary narrowing of the stocking is to be effected. The said pattern chain 85 carries the usual narrowing buttons. A second chain 85a is provided which carries a series of buttons effecting operation of the shogging motion at each and every course wherein the lace points 3 are to be actuated to produce a portion of the general design dictated by the cam unit including the cams 14, 15 and 16, under selective control of the master cam 58.

Likewise, the dipping motion, in the present instance, is the same as that used in the well known conventional types of flat knitting machines of the type noted and further detailed explanation of the construction and operation thereof is therefore deemed unnecessary in the present case.

If desired, the unit composed of cams 14, 15 and 16 may be rotated by hand, in cases, such for example, as when for some reason or other, it is desirable to eliminate or nullify a portion of the design determined collectively by the said plurality of cams, in which case a hand wheel 90 is loosely mounted on the shaft 13 and is held outwardly on said shaft against a stop head 13a by a spring 91. The hand wheel 90 is provided with an inwardly extending finger 92, the free end of which is disposed substantially opposite and adjacent the teeth of the ratchet wheel 17, whereupon, by moving the hand wheel 90 inwardly against the action of the spring 91 and said free end of the finger 92 engages one of the teeth of the ratchet wheel 17 and locks the said hand wheel to the ratchet wheel, whereupon rotation of the hand wheel 90 will rotate the ratchet wheel 17 and the cam unit operatively connected therewith in the manner above noted to nullify any desired portion of the sum total of the lengths of all the cam tracks 14, 15 and 16 as selectively thrown into successive use by the master cam 58 during one complete operating cycle of the said master cam. Upon releasing the hand wheel 90 the spring 91 will return said hand wheel to its outer inoperative position, releasing the finger 92 from the ratchet wheel 17 to permit normal operation thereof.

Of course, the improvements specifically shown and described can be changed and modified in various ways without departing from the invention herein disclosed and hereinafter claimed.

I claim:

1. In a straight knitting machine, pattern control mechanism comprising a multi-cam-track unit, a cam follower, a master cam, means operable by said master cam for selectively correlating said cam follower with any one of the cam tracks of said unit, means for effecting actuation of the selective correlating means at a predetermined point in the period of correlation of the cam follower with a previously selected cam track for making a new selection, and means for withholding the cam follower from all of said cam tracks during the selection of one thereof.

2. In a straight knitting machine, pattern control mechanism comprising a series of axially aligned disc cams, a cam follower mounted beyond the peripheries of said cams for movement laterally of said cams into a position substantially in the plane of any one of said cams, a master cam, means cooperating with said master cam

for aligning the cam follower with a cam selected by said master cam, means for intermittently rotating said cams to effect operation of the cam follower and said cam follower aligning means, 5 and means carried by one of said selectable cams for rendering said master cam effective at a predetermined point in the rotation of the selected cam.

3. In a straight knitting machine including a series of needles, a point bar arranged to dip toward the needles, a unitary pattern control mechanism including an axle supporting a series of pattern cams capable of unitary movement, a normally inactive control cam, also supported by 10 said axle, each said control cam and pattern cams capable of movement relative to each other, and separate racks operating said pattern cams and said control cam, and deriving their actuating motion from the same source.

20 4. In a straight knitting machine, the combination with a mechanism for producing loops formed by the coaction between a point member and selected needles, of a compact unit control structure for said loop-forming mechanism adapted to be mounted on the dipping rod of said machine, comprising a plurality of cams, a cam follower, a master cam, and means operable by 25 said master cam for selectively correlating said cam follower with any one of the said plurality of cams.

30 5. In a straight knitting machine, the combination with a mechanism for producing loops formed by the coaction between a point member and selected needles, of a compact unit control structure for said loop-forming mechanism adapted to be mounted on the dipping rod of said machine, comprising a multi-cam-track unit, a cam follower, a master cam, means operable by 35 said master cam for selectively correlating said cam follower with any one of the cam tracks of said unit, and means for moving the cam follower out of camming engagement with said unit during the selecting operation of said master cam.

40 6. In a knitting machine having a series of needles, a dipping rod and a point rod arranged to dip toward the needles, a special loop-forming unit mounted on said dipping rod and comprising pattern cams having peripheral surfaces for progressive coaction with a follower for operating the point rod of said machine and collectively providing a cam track of greater length than the track of a single circular cam of equal 45 average diameter, a master cam movable relative to the pattern cams, means actuating said pattern cams during the dipping motion of the narrowing mechanism of said machine, means for operating the master cam in predetermined relation to operation of the pattern cams, and mechanism including a follower responsive to operation of the master cam for shifting the pattern-cam follower from one to another of the pattern cams.

50 7. In a knitting machine having a series of needles, a dipping rod and a point rod arranged to dip toward the needles, a special loop-forming unit mounted on said dipping rod and comprising pattern cams having peripheral surfaces for progressive coaction with a follower for operating the point rod of said machine and collectively providing a cam track of greater length than the track of a single circular cam of equal 55

average diameter, a master cam movable relative to the pattern cams, means actuating said pattern cams during the dipping motion of the narrowing mechanism of said machine, and including a pawl-and-ratchet device for actuating the pattern cams, means including an element on one of the pattern cams and a pawl-and-ratchet device for operating the master cam in predetermined relation to operation of the pattern cams, and mechanism including a follower responsive to operation of the master cam for shifting the pattern-cam follower from one to another of the pattern cams. 10

8. In a knitting machine, the combination with a loop-forming mechanism, of a cam unit adapted to be mounted on the dipping rod of said machine, including a plurality of cam structures, one of said cam structures operating intermittently and the other of said cam structures operating in timed relation with respect to 15 the first cam structure, one of said cam structures including a plurality of cams, the camming surfaces of which constitute, in effect, peripheral sub-divisions of a single larger cam as related to a given pattern, a cam follower shiftable from 20 one of said subdivision cams to another, and means responsive to operation of the machine for shifting the follower between the subdivision cams of said one cam structure in any desired sequence. 25

9. In a knitting machine, the combination with a loop-forming mechanism, of a control unit adapted to be mounted on the dipping rod of said machine including a plurality of cams cojointly defining a unit design element, the cam surface of each of said cams defining a component part of said design element, and means including a cam follower responsive to operation of the machine for movement in either direction during the same cycle and from any one to another 40 of the cams in any desired sequence and to control said mechanism. 30

10. In a knitting machine, the combination with a loop-forming mechanism, of a unit control device adapted to be mounted on the dipping rod of said machine including a support, a cam follower, a plurality of pattern cams, a master cam for controlling movement of the follower relative to the pattern cams, all of said cams mounted on the same axis, and means on 45 one of the pattern cams for controlling operation of the master cam. 50

11. A special loop-forming mechanism, for a full-fashioned knitting machine, including pattern cams having camming surfaces constituting in effect, perimetral subdivisions of a single cam of substantially greater diameter defining a like pattern, a picot cam, a master cam movable relative to the pattern cams, means actuating said pattern cams and picot cam during the dipping motion of the narrowing mechanism of said machine, means for operating the master cam in predetermined relation to the operation of the pattern cams, means including a follower responsive to operation of the master cam for shifting the pattern-cam follower back and forth between positions in which it is respectively operatively related to one of the pattern cams, and means for shifting the pattern cam follower to position cooperating with the picot cam. 55 60 65 70
